UNITED STATES PATENT OFFICE.

JOSEPH STERN, OF SAN FRANCISCO, CALIFORNIA.

COLLAR.

SPECIFICATION forming part of Letters Patent No. 507,045, dated October 17, 1893.

Application filed April 5, 1893. Serial No. 469,125. (No model.)

To all whom it may concern:

Be it known that I, JOSEPH STERN, a citizen of the United States, residing at San Francisco, in the county of San Francisco and State 5 of California, have invented a new and useful Collar, of which the following is a specification.

This invention relates to collars, and has special reference to fastening means for the 10 same, and the object thereof is to dispense with the use of a collar-button at the back by making an integral fastening on the collar or connect the same thereto, and avoid chafing or rubbing of the back of the neck.

15 With these and other objects in view, the invention consists of the construction and arrangement of the parts thereof as will be hereinafter more fully described and claimed.

In the drawings: Figure 1 is a perspective view looking toward the inside of a lay-down collar, and a portion of a neck-band, showing the improved fastening connecting the two parts. Fig. 2 is a similar view and arrangement of a standing collar. Fig. 3 is a plan 25 view of a lay-down collar unfolded, showing the improved fastening in connection therewith. Fig. 4 is a view similar to Fig. 3 of a standing collar shown supplied with the fastening. Fig. 5 is a detail perspective view of 30 the rear portion of a collar-band on an enlarged scale, showing the improved fastening in connection therewith and illustrating in dotted lines the positions of the corners of the head when folded for insertion through a button-hole.

35 Similar numerals of reference indicate corresponding parts in the several figures of the drawings.

Referring to the drawings, the numeral 1 40 designates a collar of either folded or standing form and of suitable shape or material, having the back central part thereof formed with a depending arrow-head-shaped tongue or fastening 2, with angular slots 3 on opposite sides of the same, and consisting of a lower triangular-shaped head 4, with corners 5, that are arranged to be bent inwardly toward each other to contract this portion of the tongue or fastening for insertion through 45 a button-hole, and a neck 6, that extends

from the body of the collar and may be either integrally formed with or applied to said body.

In attaching a collar having the improved tongue or fastening, the corners 4 are bent inwardly toward each other, as before stated, 55 in order to permit the said tongue or fastening to be inserted through the button-hole, and after said insertion the said corners are permitted to assume their normal position and provide shoulders 7, that extend laterally a greater distance than the length of the button-hole and thereby the tongue or fastening is prevented from becoming accidentally disengaged from the button-hole. The 60 said tongue or fastening will be reinforced at such points as may be found necessary, and may be made of any number of plies, it being seen that the line of stitching along the lower edge of the collar is carried out through the tongue or fastening that firmly secures 65 the edges of the same against separation. It will be observed that the tongue or fastening being without material surface projection will not interfere with the proper laundering of linen or fabric collars, and in the makeup 70 of such class of collars the said tongue or fastening can be cut at the same time as the remaining portion of the collar.

It will be observed that the rear portion of the collar-band is cut away to form a V-shaped notch 8, within which is located the tongue or fastening which is integral with the collar-band, the said tongue or fastening terminating at its lower end at or near the line of the lower edge of the collar-band. It will 85 also be understood that the tongue or fastening may be conveniently employed in connection with paper collars, and in whatever connection the attachment may be used it will dispense with the use of a collar-button at the 90 back of the neck-band with the consequent advantage arising from a disuse of said device.

Changes in the form, proportion, and the minor details of construction may be resorted to without departing from the principle or 95 sacrificing any of the advantages of this invention.

Having described the invention, what is claimed as new is—

1. A collar provided with a cut-away por- 100

tion or opening, and a tongue arranged in said opening and having lateral shoulders to engage a button-hole, substantially as specified.

2. A collar having its band cut away to form
5 a V-shaped opening, and an arrow-shaped tongue arranged within said opening to engage a button-hole, substantially as specified.

In testimony that I claim the foregoing as my own I have hereto affixed my signature in the presence of two witnesses.

JOSEPH STERN.
